(57) **CLAIM**

The ornamental design for a cart, as shown and described.

DESCRIPTION

FIG. 1 is a front isometric view of my new design for a cart.

FIG. 2 is a left side elevation view of FIG. 1.

FIG. 3 is a right side elevation view of FIG. 1.

FIG. 4 is a front elevation view of FIG. 1.

FIG. 5 is a back elevation view of FIG. 1.

FIG. 6 is a top plan view of FIG. 1; and,

FIG. 7 is a bottom plan view of FIG. 1.

The broken lines shown in the figures are for the purpose of illustrating portions of the cart that form no part of the claimed design.

1 Claim, 6 Drawing Sheets(56)
